UNITED STATES PATENT OFFICE.

WILLIAM H. GASKILL, OF PHILADELPHIA, PENNSYLVANIA, ASSIGNOR TO
SAMUEL W. EVANS, JR., OF SAME PLACE.

DESIGN FOR AN UMBRELLA-RUNNER.

SPECIFICATION forming part of Design No. 33,847, dated January 8, 1901.

Application filed November 20, 1900. Serial No. 37,180. Term of patent 14 years.

To all whom it may concern:

Be it known that I, WILLIAM H. GASKILL, a citizen of the United States, residing in the city and county of Philadelphia, in the State of Pennsylvania, have invented and produced a new and original Design for Umbrella-Runners, of which the following is a specification, reference being had to the accompanying drawings, forming part thereof.

10 The leading feature of my design for an umbrella-runner is a body having a reduced part at its lower portion and a narrow bead at its upper extremity, adjacent to a slotted ring.

15 Figure 1 represents a perspective view of an umbrella-runner embodying my design, having a portion of its upper end broken

away. Fig. 2 represents a longitudinal sectional view thereof. Fig. 3 represents a perspective view thereof.

20 In the drawings, A designates an umbrella-runner having the cylindrical body B and the reduced part C, said body being provided with a narrow bead D adjacent to the slotted ring E.

Having described my invention, what I claim as new, and desire to secure by Letters Patent, is—

25 The design for an umbrella-runner substantially as shown and described.

WILLIAM H. GASKILL.
